UNITED STATES PATENT OFFICE.

LORETTA M. JUSTICE, OF LOUISVILLE, OHIO.

LUNCH-CASE.

No. 904,440.

Specification of Letters Patent.

Patented Nov. 17, 1908.

Application filed May 2, 1908. Serial No. 430,561.

To all whom it may concern:

Be it known that I, LORETTA M. JUSTICE, a citizen of the United States, residing at Louisville, in the county of Stark and State 5 of Ohio, have invented new and useful Improvements in Lunch-Cases, of which the following is a specification.

This invention relates to lunch cases, the object of the invention being to provide a 10 simple, convenient and practical box or case for carrying eatables including a beverage, such as coffee, the casing embodying a plurality of compartments and drawers for the reception of different articles which are thus 15 kept separated from each other and also including a novel arrangement of flask for carrying coffee, tea, milk, or the like, including means for holding said flask securely in position and preventing the escape of the 20 stopper and the spilling of the contents thereof in the ordinary handling.

With the above and other objects in view, the invention consists in the novel construction, combination and arrangement herein- 25 after, described, illustrated and claimed.

In the accompanying drawings: Figure 1 is a perspective view of a lunch case embodying the present invention, showing the same closed. Fig. 2 is a front elevation 30 thereof shown open, with the cover partly broken away in section. Fig. 3 is a vertical transverse section through the same, and Fig. 4 is a plan view of one of the compartment drawers.

The improved lunch case comprises a box shape main section 1 and a comparatively shallow complementary section 2 which forms a combined tray and cover for the main section 1, said cover being flanged, as shown, to 35 form a marginal rim for the tray when moved outward to a horizontal position, as shown in Figs. 2 and 3. The case is provided at the top with a suitable carrying handle 3 having enlarged ends 4, held by 40 metal loops 5 secured to the top of the case, while the cover 2 is provided with a spring catch 6 adapted to snap into engagement with a shoulder or projection 7 on the main section 1, as shown in Fig. 1. It will also be 45 noted that the cover 2 is hinged to the section 1, as shown at 8 so that it may fold downwardly to a horizontal position, as

shown in Figs. 2 and 3, where it forms a tray for holding various articles.

Within the upper portion of the main section 1 there are arranged compartment drawers 9 and 10 provided with suitable handles 11 to facilitate the insertion and removal thereof, said drawers being supported upon cleats 12 secured to the inner surface 55 of the opposite ends of the case as shown in Fig. 2. One or both of the drawers 9 and 10 may be provided with any desired number of partitions 13 to divide the same into compartments for holding articles separated 60 from each other. Beneath the lowermost drawer 10 there is a space for a drinking cup 14 and salt and pepper cruetts 15 and 16. The lower portion of the case is also provided with a double spring clip 17 for clasping and holding the cruetts 15 and 16 to prevent the accidental dislodgment of the same 65 in handling the case. The remaining portion of the lower part of the case is adapted for the reception of a flask 18 adapted to 70 contain coffee, tea, milk, or the like, the same being in the form of a drawer provided with a handle 19. The flask 18 is arranged to fit between one of the cleats 12, above described, and a similar cleat 20 against which 75 the opposite side of the flask bears, as shown in Fig. 2, while the flask is of such size as to be securely held between the back and front of the case. This prevents movement of the flask 18 in all directions. At one end the 80 flask is provided with a laterally projecting and upwardly opening spout 21 adapted to receive a cap or stopper 22 and just beneath the drawer 10 there is arranged a horizontal strip 23 forming a guard beneath and against 85 which the stopper 22 rests, the guard thereby preventing the accidental displacement of the stopper and incidentally preventing the spilling of the liquid contents of the flask.

The case herein above described will be 90 found very convenient to the workman and will withstand considerable rough handling without danger of spilling the contents thereof.

Having described the invention, what I 95 claim as new is:—

A lunch case comprising a main section, a combined tray and cover hinged thereto, a series of compartment drawers mounted in

said case, a sliding flask provided with a laterally projecting and upwardly opening spout at one end thereof, cleats by which the flask is guided and held against movement, and a horizontally extending guard strip beneath and against which the stopper of the flask bears when said flask is in position in the case, substantially as described.

In testimony whereof I affix my signature in presence of two witnesses.

LORETTA M. JUSTICE.
